UNITED STATES PATENT OFFICE.

ROBERT E. ADAMS, OF HARRISBURG, PENNSYLVANIA.

COMBINATION BAGGAGE.

Application filed June 30, 1923. Serial No. 648,720.

To all whom it may concern:

Be it known that I, ROBERT E. ADAMS, a citizen of the United States, residing at Harrisburg, in the county of Dauphin and State of Pennsylvania, have invented certain new and useful Improvements in Combination Baggage, of which the following is a specification.

This invention relates to baggage, and 10 more particularly to combination outfits for use for various purposes.

While well adapted for travelers, campers, etc., the present invention is especially designed to meet the needs of seamen in 15 the Navy.

In its broader aspects, the main object of the invention is to provide an article of baggage, of elongated form, having a central compartment formed of relatively rigid 20 material, and end compartments formed of soft, flexible material, whereby, when the baggage is thrown about, or allowed to fall from considerable heights, as is often the case, the flexible end compartments, especially 25 when filled with soft clothing, will act as a cushion to absorb the shocks, and protect the middle compartment from breakage. A further object of the invention is to provide an article of baggage, of 30 the above character, in which the central compartment is complete in itself, and may be separated from the end compartments, and used alone as a hand bag or satchel.

More specifically, the present invention 35 seeks to combine in one piece of baggage the usual "duffle bag" and "ditty box," with which seamen are now commonly equipped, so as to make it necessary to handle and care for only one article instead of two, and 40 so that the box portion will be protected by the bag portion thereof.

In order that the invention may be readily understood, reference is had to the accompanying drawing, in which:—

45 Fig. 1 is a side elevation of my improved article of baggage complete;

Fig. 2 is a central longitudinal section through the same;

50 Fig. 3 is a side elevation of the central compartment as it appears when separated from the other compartments;

Fig. 4 is a transverse section through the central compartment showing the hinged door;

Fig. 5 is a fragmentary similar view on 55 an enlarged scale;

Fig. 6 is a fragmentary transverse section on an enlarged scale on the line 6—6 of Fig. 1; and

Fig. 7 is a transverse fragmentary section 60 on an enlarged scale showing the method of securing the canvas to the central container.

Referring to the drawings in detail; my improved article of baggage is preferably 65 of elongated cylindrical form and comprises a central compartment A and two end compartments B and C. The central compartment has its walls formed of comparatively rigid, stiff material such as sole 70 leather or hard fibre or press board, and is in the nature of a box, having cylindrical side walls 1, flat end walls 2, and also preferably two or more partitions 3 dividing the interior into a series of chambers or 75 receptacles.

The end walls 2 are provided with pressed up flanges 2^a which fit within the side walls 1 and which may be riveted or sewed thereto. The partitions 3 also are formed with 80 pressed up flanges 3^a, which may be similarly secured. These flanges do not extend entirely around the periphery of the partitions, the flanges stopping at the edges of a hinged door 4, as clearly shown in Figs. 2 85 and 4. This door 4 forms part of the cylindrical surface of the central compartment or container, and is hinged thereto at one longitudinal edge, as indicated at 5. If the container is constructed of leather, the 90 leather may be simply scored as shown at 5, in Fig. 5, but if made of fibre or press board, suitable hinges either of metal or 95 flexible material may be provided.

The hinged portion or door 4 is preferably 100 of rounded or tapering form at its front edge, as shown in Fig. 3, and a stop strip 6 extends entirely around the edge of this door, as shown in Figs. 3 and 6, and constitutes a flange adapted to engage the 105 adjacent edge of the cylindrical wall 1.

A suitable lock, preferably of the trunk type, is provided, for locking the door in its closed position, such lock comprising a swinging hasp 7 and a lock, proper, 8.

Extending over and enclosing the central rigid container A is a flexible covering 9 made of canvas or similar textile material.

This cover fits tightly around the cylindrical walls of the container A and may be secured thereto by means of lacing 10 passing through holes in the cover and corresponding holes in the edge of the portion 1 and the flanges 2^a. This canvas covering is provided with a flap 11 which is adapted to overlie and substantially register with the hinged door 4. This flap carries at its point 10 a loop 12 through which passes a strap 13 secured to the canvas covering at 14 and carrying at its free end a ring 15. A similar ring 16 is carried by a loop fixed to the canvas covering and a pad lock 17 may be engaged with both rings 15 and 16, thus securely locking the flap in closed position. It will therefore be observed that independent means are provided for locking both the hinged door 4 and the flap 11.

20 In addition to this, the edges of the flap may be secured by means of lacing 18 if desired, as shown in Fig. 1.

The canvas covering 9 is extended at each end, as indicated at 19 to form the end containers or compartments B and C. These compartments have flexible walls, being constructed wholly of canvas or the like, and having in them no rigid parts whatever.

The canvas cover is, as above stated, extended a suitable distance beyond each end of the central container or compartment, as indicated at 19, and inside the free ends of such extended portions are secured, as by stitching 21, annular flaps or flanges 20. Fitting over these flaps or flanges, and telescoping therewith are end sections 23 also formed of canvas and having end walls to which suitable handles 25 are secured. The free edges of the extensions 19, beyond the 40 seams 21, are provided with series of eyelets 22, and similar series of eyelets are set in the inner edges of the end sections 23, as shown at 24. Suitable lacing 26 is threaded through these eyelets and serves to hold the two sections of each of the end compartments together.

By virtue of this construction, the end compartments are rendered longitudinally adjustable or expansible so that by loosening or tightening up on the lacing, these compartments may be made to have greater or less capacity, as may be required. In Figs. 1 and 2, the compartment B is shown as contracted to its minimum capacity, while the 55 compartment C is illustrated as expanded to a greater capacity.

In practice, the central compartment A will be used to contain toilet articles and the like, or, in fact, anything of a hard or rigid nature, or which it is desired to protect from breakage or injury. The end compartments, on the contrary, will be employed to contain clothing or other soft material. When these end compartments are filled with soft material or articles, it will be apparent that

they act as cushions and thereby protect and prevent injury to the central compartment.

When used by seamen, the central compartment will take the place of the usual "ditty-box", while the end compartments, 70 containing clothing, will serve the purpose of the ordinary sea bag or "duffle bag". I have thus provided a single article of baggage which can be substituted for the above mentioned two separate articles with which 75 seamen have heretofore been equipped.

Baggage of the character to which this invention relates is usually subjected to extremely rough handling, especially in the Navy, and it is of the utmost importance, 80 therefore, that the baggage be so constructed as to successfully withstand the severe shocks to which it is often subjected. When one of my improved bags is packed, as above described, with the flexible end compartments 85 filled with soft clothing, so as to constitute cushions, it may be thrown about freely and even dropped from the deck of a ship to the wharf without damage.

It will also be observed that access may be 90 had to the end compartments without opening the middle compartment, and vice versa. Moreover, upon certain occasions when desired, the canvas covering may be entirely removed from the central container by taking out the lacing 10, and this container, when thus separated from the canvas covering will, in itself, constitute a complete piece of baggage, as shown in Fig. 3, and may be used like an ordinary grip or hand bag. 95 When so used, a carrying device in the nature of a "shawl strap" is employed, this device comprising a bar 27 to which a handle is attached, and a pair of straps 28, arranged to encircle the container.

100 The canvas covering, too, when the central container is removed, can be used independently as a piece of baggage similar to the ordinary sea bag.

105 It will thus be seen that I have provided a combination article of baggage which lends itself readily to a variety of uses, which is simple and cheap in construction, convenient in use, and almost indestructible, and moreover, a combination article from 110 which one of the parts may be separated to serve as an independent container, and it is thought that the many advantages of my invention will be readily appreciated without further discussion.

115 What I claim is:—

1. An article of baggage of elongated form and comprising a central and two end compartments, the central compartment having walls made of relatively stiff material, 125 and the end compartments having side walls of flexible material.

2. An article of baggage of elongated form and comprising a central and two end compartments, the central compartment hav- 130

ing walls made of relatively stiff material, and the end compartments having side walls of flexible material, said compartments having substantially the same cross-section and 5 being separable, and the central compartment, when separated, constituting a complete receptacle in itself.

3. An article of baggage of elongated form and comprising a central and two end compartments, said end compartments having side and end walls formed substantially wholly of flexible textile material, whereby they serve as cushions to absorb shocks.

4. An article of baggage of elongated form, and comprising a central and two end compartments, all of said compartments being of substantially uniform cross-section, throughout, the sidewalls of the central compartment being made of relatively rigid material, and the side walls of the end compartments being made of relatively flexible material.

5. An article of baggage of elongated form, and comprising a central and two end compartments, the side walls of the central compartment being formed of relatively rigid material, and the side walls of the end compartments constituting substantially continuations of the side walls of the central compartment and being made of relatively flexible material.

6. An article of baggage comprising a rigid container and a covering formed of textile material, encasing the same, said container and covering being separable, whereby when separated, each constitutes a complete independent receptacle in itself.

7. An article of baggage of elongated form and comprising a central and two end compartments, said end compartments having side walls formed wholly of flexible textile material, and each end compartment be-

ing made up of two sections, telescoping together, whereby said compartments are longitudinally expansible.

8. An article of baggage comprising a container formed entirely of flexible material and made up of two sections, one section terminating in an annular flap or flange, and the other section telescoping over said flap 50 or flange, whereby said container is rendered expansible or adjustable in size, and lacing for securing said sections together.

9. An article of baggage comprising a rigid container, and a covering of textile 55 material encasing the same, said covering being extended at each end to form a pair of flexible containers.

10. An article of baggage comprising a rigid cylindrical container, and a separable 60 textile covering encasing the same, said covering being extended at each end to form a pair of flexible cylindrical containers of substantially the same diameter as the rigid container.

11. An article of baggage comprising a rigid cylindrical container, and a separable textile covering encasing the same, transverse partitions in said container dividing the same into a series of chambers, said container having a hinged portion affording access to all of said chambers, and said textile covering being formed with a flap of substantially the same size and shape as the hinged portion of the container.

12. An article of baggage comprising a rigid cylindrical container, and a separable textile covering encasing the same, said container having a hinged door, and said textile covering having a flap overlying said 80 door, and means for independently locking both said door and flap.

In testimony whereof I affix my signature.
ROBERT E. ADAMS.
